ATTORNEY

UNITED STATES PATENT OFFICE

CHARLES HAMMER, OF NEW YORK, N. Y., ASSIGNOR, BY MESNE ASSIGNMENTS, TO ANCHOR CAP & CLOSURE CORPORATION, OF LONG ISLAND CITY, NEW YORK, A CORPORATION OF NEW YORK

SEALED PACKAGE

Application filed September 14, 1929. Serial No. 392,535.

This invention relates to an improvement in receptacle closure caps and more particularly to a closure cap which can be readily removed and can be applied afterwards as 5 a reseal closure.

Closure caps on the market today are designed either to improve the seal of a package to which they are applied or to facilitate easy removal therefrom. Some of the caps 10 are screwed on and off containers. These cannot be fastened to the container as quickly as caps having loosely fitted threads that can be applied with a slight vertical force. Ordinary screw caps are likely to "freeze" 15 on the container to be applied too tight and, therefore, lack the feature of easy removal. Other closures frequently used comprise a working seal, such as a "crown cork" cap, and a second cap screwed over the said working seal onto the mouth of the container. 20 Special machinery is required to apply such a seal to the container and two caps are required; consequently, the cost of the caps and the time of applying the seal are much greater 25 than for a cap with a combined sealing and screw portion.

Caps having a tear-off band to facilitate removal are subject to several objections. The tear-off band often departs from its intended 30 line of severance and only a portion of the band is removed. This necessitates the employment of tools to remove the cap, which usually results in mutilating the cap, thus rendering it unfit to be used again. Another 35 serious objection is that the tear-off band on these caps leaves sharp edges which readily cause injury to the hands of the consumer. A tear-off strip having the usual finger grip is likely to slip between the fingers when the 40 package is opened, thus inflicting upon the consumer cuts or other injuries.

Closure caps are made from thin sheet tin or other metal and, where scored lines are used, their depth must be very accurately 45 gauged otherwise the metal may be severed or else not scored deep enough to permit it to tear. The accuracy required has made such caps very objectionable to manufacturers. 50 Slight wear impairs the adjustment of the

scoring tools and causes complaints by customers.

The closure cap of the present invention has been designed to eliminate the difficulties encountered in removing the tear-off strips 55 by confining the tear to the score to prevent severance of the strip during the tearing operation. In addition, the construction of the strip prevents slipping between the fingers and possible injuries resulting therefrom. It 60 also minimizes the difficulties of removal occasioned by the score line being of improper depth and gives the cap manufacturer a greater tolerance in forming the score. The advantages of such a closure cap are beneficial 65 both to manufacturer and consumer.

An object of the invention is to provide an improved, inexpensive closure cap adapted to be readily applied to receptacles and to form a hermetic seal therewith.

Another object of the invention is to provide an improved closure adapted to be readily removed without the employment of tools.

Another object of the invention is to provide an improved closure cap which, after 75 being removed, can be applied to re-close or reseal the receptacle, thus preventing loss of the contents and permitting the contents to be dispensed directly from the receptacle.

Another object of the invention is to provide an improved closure cap having a depending skirt comprising a removable strip constructed to confine the severance to a scored line and to prevent mutilation of the strip.

Another object of the invention is to provide an improved sealed package which cannot be opened or tampered with without leaving visible indications thereof.

Another object of the invention is to provide a closure cap having a tear-off strip which may be readily gripped without danger of the strip injuring the fingers.

A further object of the invention is to provide a tear-off strip which is not likely to 95 break during the tearing operation.

Other and further objects of the invention will be obvious upon an understanding of the illustrated embodiment about to be described or will be indicated in the appended claims, 100

and various advantages not referred to herein will occur to one skilled in the art upon employment of the invention in practice.

A preferred embodiment of the invention ⁵ has been chosen for purposes of illustration and description and is shown in the accompanying drawing, forming part of the specification, wherein

Fig. 1 is a side elevational view of a preferred embodiment of the cap, partly in section, illustrating the closure as it appears attached to a receptacle;

Fig. 2 is a perspective view of the cap showing the tear-off strip partially removed;

Fig. 3 is another embodiment of the invention;

Fig. 4 illustrates a different construction embodying the invention; and

Figs. 5, 6 and 7 illustrate further applications of the invention.

Referring again to the drawing illustrating a preferred embodiment of the invention, and referring more particularly to Figs. 1 and 2 thereof, there is shown a container 1, here illustrated as a chili sauce bottle, with a cap 2 secured thereon. For purposes of illustration, the cap is shown having a top portion or button 4 and a depending skirt or body part 5 formed from a strip of metal bent ²⁵ into a cylindrical shape with the free ends interlocked, the button and body part being secured together by an interfolded seam 6. It will be understood, of course, that the present invention is applicable to caps other than ³⁰ those made in two pieces as illustrated.

The cap may be provided with screw threads 7 extending about the body portion thereof to engage corresponding threads 8 on the mouth of the container. These interlocking threads may be sufficiently loose to permit the cap to be forced over the threads on the container by downward pressure without the usual rotative movement. The purpose of this is to facilitate application of the cap. ⁴⁰ The threads are used primarily for resealing operations. The upper part of the cap may be knurled or provided with corrugations 9 to facilitate manual grip for the resealing operation.

A shoulder 10 is provided on the container adjacent the bottom of the skirt of the cap and the lower edge of the skirt of the cap is rolled under the lower edge of the shoulder to hold the cap in position. In the sealing operation, a suitable pressure is applied to the cover part of the cap to seat the gasket firmly against the rim of the container and to hold it in sealed position until the crimping operation folds the lower edge of the cap ⁵⁵ under the shoulder 10. In order to facilitate removal, the cap is provided with a score 12 which, essentially, is a scored line cutting partially, but not entirely, through the metal of the cap to weaken it so that the lower strip 14 on the bottom of the skirt may be

readily removed to permit the unscrewing of the upper part of the cap. A suitable notch ⁷ 13 may be provided, if desired, the apex of which meets the scored line so that the tearing operation may be started without difficulty. A tongue 15 may also be provided to furnish the consumer with a ready hold on the strip.

In order to further facilitate the removal of this strip, there is provided a series of corrugations or other indentations 16 directly below the scored line 12, and a second series of corrugations or other indentations 17 directly above the scored line. Preferably, these corrugations are also provided in the tongue 15. In tearing the strip where the metal is plain, there is an inclination for the strip to break or tear across rather than to confine itself to the scored line. This is particularly true where the score is not as deep as it might be. Great difficulty has been experienced in maintaining the high accuracy required in forming the score of proper depth due to the thinness of the metal.

By forming the corrugations 16 under the removable band 14 adjacent to the scored line, the consumer in removing the cap has a corrugated part to grip which is easy to hold without slipping and injuring fingers. In addition, experiment has demonstrated that the tear will not proceed through or between the corrugations but will confine itself to the scored line. This is partially because of the reinforcement occasioned by the corrugations. Furthermore, due to the fact that the metal has already been bent in this portion of the cap, there is a greater flexibility and the tongue 15 may be more easily raised and pulled around to effect the tearing operation. In other words, the corrugations give greater flexibility in a circumferential direction as the strip is partially torn, and greater strength in a vertical direction. This enables the strip to be readily held and is effective to produce a smooth tear which is confined to the scored line. The corrugations 17 above the scored line operate to prevent the tear proceeding upwardly, thereby co-operating with the corrugations 16 to confine the tearing to the proper place. The formation of the corrugations or other indentations does not require any additional metal in the cap or any additional rolling operation in the manufacture of the cap. The rolls may be changed to effect this operation with the same machinery and the same steps heretofore utilized. The corrugations above or below the line may end a short distance from the scored line without materially affecting the desired result.

In Fig. 3, a construction is illustrated wherein the corrugations are in the tear-off strip but are not provided above the scored line. The advantage of this construction is that the reinforced band will not tear across

the corrugation, the hand grip is not impaired and, at the same time, a greater space is allowed in the upper part of the cap for the threads 7.

5 Certain constructions provide a pair of scored lines which permit the band of metal therebetween to be removed so that the upper and lower part of the cap may be separated. Such a construction is shown in Fig. 10 4 wherein a pair of scored lines 18 are illustrated with a band of metal therebetween corrugated, as shown at 19. The operation of the construction is substantially similar to those described hereinbefore.

25 Fig. 5 is similar to Fig. 4 with corrugations 19 intermediate the scored lines 18 and with corrugations 20 above and below the scored lines 18.

Fig. 6 is similar to Figs. 1 and 2 except 20 that the notch 13 is omitted and the corrugations above and below the scored line 12 are inclined to perpendicular. Such a construction gives a nice appearance and effects the advantage of confining the tear and, to 25 a certain extent, the advantage of creating flexibility in the portions of the strip severed from the cap.

Fig. 7 illustrates the invention applied to 30 a one-piece closure with the corrugations 16 provided in the tear-off band, as illustrated in Fig. 3. The tongue 15 may be entirely or partially cut in the skirt of the cap or may be formed in any other suitable manner.

It will be seen that a very inexpensive 35 closure is provided which has advantages not possessed by previous caps. The corrugations in the cap do not break the metal or the lacquer thereon and, hence, present no additional surfaces likely to rust but, on the other hand, actually improve the appearance of the 40 cap. In addition, these corrugations confine the tear to a scored line and prevent the tear-off strip from breaking during the tearing operation. Furthermore, the corrugations in 45 the tongue, as well as in the rest of the tear-off strip, provide a very effective grip which prevents the strip from slipping between the fingers and inflicting injury. The application of the cap to the container is greatly facilitated, as well as its removal. A re-seal 50 closure is provided so that the contents of the container may be dispensed therefrom if desired.

It will be understood that while the present invention is particularly adapted for 55 closure caps, many of its features may be utilized wherever scored lines are employed. As various other changes may be made in the form, construction and arrangement of the 60 parts herein without departing from the spirit of the invention, it is to be understood that all matter herein is to be interpreted as illustrative and not in a limiting sense.

Having thus described my invention, I 65 claim:

1. As an article of manufacture, a closure cap comprising a cover portion, a depending skirt, said skirt being weakened to provide a tear-off strip, and corrugations spaced slightly apart from said weakened portion to facilitate removal of said strip. 70

2. As an article of manufacture, a closure cap comprising a cover portion, a depending skirt, said skirt having a score therein partially severing the metal to provide a tear-off 75 strip, and corrugations spaced slightly apart from said score to reinforce said skirt and to facilitate removal of said strip.

3. As an article of manufacture a closure cap having a depending skirt, a portion of 80 said skirt being connected thereto by a scored line to provide a tear-off strip, and corrugations spaced slightly apart from said scored line to confine the tearing along the scored line. 85

4. As an article of manufacture, a closure cap having a score partially cutting the metal extending circumferentially about the skirt thereof and corrugations immediately above and apart from said scored line. 90

5. As an article of manufacture, a closure cap having a score partially cutting the metal extending circumferentially about the skirt thereof and corrugations immediately above and immediately below said scored line, said 95 corrugations being spaced apart from said scored line.

6. As an article of manufacture, a closure cap comprising a cover portion and a depending skirt, a tear-off strip at the lower part of 100 the skirt connected therewith by means of a scored line, the end of said strip being in the form of a tongue to facilitate the tearing of the strip, and corrugations extending transversely of said strip and said tongue to facilitate gripping of the tongue and to prevent breaking of the strip in the tearing operation. 105

7. As an article of manufacture, a sealed package comprising a container having a shoulder adjacent the upper end, a closure cap adapted to fit about the upper end of said container, the lower part of said cap being turned inwardly under said shoulder to hold said cap in position, a scored line extending circumferentially of the cap to permit the lower portion thereof to be torn off for removal thereof, and corrugations spaced slightly away from said scored line to confine the tearing to the scored line and to prevent severance of the tear-off strip during the tearing operation. 115

8. As an article of manufacture, a closure cap comprising a cover portion, a depending skirt, said skirt having a strip secured thereto by a scored line, a tongue integral with said strip, and corrugations extending transversely of said tongue to facilitate gripping thereof. 125

9. As an article of manufacture, a closure cap comprising a cover portion, a depending 130

skirt, said skirt having a strip secured thereto by a scored line, a tongue integral with said strip having a greater width than said strip to facilitate manual gripping thereof, corrugations extending transversely of said tongue to provide a gripping surface, and other corrugations above said scored line to confine the tear to the scored line.

10. In a sealed package, the combination of a glass container having threads at the mouth thereof, and a closure cap comprising a depending skirt, a portion of said skirt being connected thereto by a scored line partially severing the metal thereof to provide a tear-off strip, corrugations spaced slightly apart from said scored line to confine the tearing along the scored line, and thread engaging means in said skirt adapted to engage the threads of the container to reseal the container when the tear-off strip has been removed.

11. In a sealed package, the combination of a glass container having threads at the mouth thereof, and a closure cap comprising a depending skirt, a tear-off strip at the lower part of the skirt connected therewith by means of a scored line partially severing the metal of the cap, the end of the strip being wider than said strip to form a tongue to facilitate tearing of the strip, corrugations extending transversely of said strip and said tongue to facilitate gripping of the tongue and to prevent breaking of the strip in the tearing operation, and threads formed in the skirt of the cap adapted to engage the threads of the container.

12. As an article of manufacture, a sealed package comprising a container having closure engaging means on the neck thereof, a closure cap having a top portion and a depending skirt, a scored line extending about the skirt of said closure cap providing a tear-off portion, said tear-off portion being constricted inwardly about said closure engaging means, corrugations in said tear-off portion adapted to strengthen the grip thereof upon the container, and corrugations in said skirt above said scored line to facilitate the tearing operation in removing the tear-off portion to open the package.

50 Signed at Brooklyn, New York, this 11th day of September, 1929.

CHARLES HAMMER.
